LIP STICK HOLDER OR THE LIKE

Simon Morrison, New York, N. Y.

Application April 15, 1933, Serial No. 666,233

6 Claims. (Cl. 206—56)

This invention relates to containers for housing material and holding it for use, such containers ordinarily being used for lipstick and other material in stick-like form.

Containers for housing stick material and holding it for use are well known; and the object of the present invention is to effect various detailed improvements in the construction of a device of this type, such improvements providing convenience and economy in manufacture, and convenience and durability in use.

Figure 1 is an elevation of a container of the present invention. On the original drawing accompanying this specification, the figure is the actual size of an embodiment suitable for holding lipstick.

Figure 2 is an elevation, on the same scale as Fig. 1, showing the lipstick projected from the container.

Figure 3 is an enlarged vertical section.

Figure 4 is a cross section on the line 4—4 of Figure 3, the scale being twice that of Fig. 3.

Figure 5 is an elevation of an interior part of the device.

Figure 6 is an elevation of an operating sleeve which in assembled relation embraces the structure of Figure 5.

Figure 7 is an elevation of an exterior casing that is applied over the sleeve shown in Figure 6.

Figure 8 is an elevation of the cover of the device with the means for holding the cover captive.

Reference will first be had to Figures 5 to 8. A tubular sheet metal guide designated as a whole by 1 is provided with an operating head 2, an exterior annular groove 3, and a longitudinally extending slot 4. Slidable within the cylindrical guide 1 is a cup-shaped carrier 6 which carries the lipstick or the like 7; and this carrier is provided with a pin 8 which projects through the slot 4 in the cylindrical guide 1. A split sheet metal sleeve 9 is provided with a helical slot 10 and a series of indentations 11 which are adapted to enter the groove 3. The split edges of the sleeve are designated by 9^a and 9^b and are always separated as shown in Figs. 6 and 4. An exterior casing 12 is provided near its mid section with an annular bead 13, and the upper portion of the casing is slotted at 14. A cover 16 which is adapted to telescope over the upper portion of the exterior casing 12 is pivotally connected at 17 to a metal slide or keeper 18.

In assembling, the cup-shaped carrier 6 is inserted in the cylindrical guide 1; and pin 8 is then forcibly driven through an undersize hole in

the side wall of the cup, the point of the pin slightly entering the far side of the cup in order to give the pin a two point bearing on the cup. The sleeve 9 is then applied over the cylindrical guide 1 and so positioned that indentations 11 enter groove 3 and pin 8 enters slot 10, both as shown in Fig. 3. The slide 18 is inserted through the slot 14 in the exterior casing 12, and the exterior casing is telescoped over the sleeve 9 with the keeper or slide 18 positioned between the edges 9^a and 9^b of the sleeve 9, as shown in Fig. 4.

It will be noted that the spaced edges 9^a and 9^b of the sleeve 9 provide a longitudinal guideway in which the slide or keeper 18 is adapted to 70 slide. This keeper 18 may be made of sheet metal slightly thinner than the metal of sleeve 9, thereby allowing the keeper to slide freely. When the cover is not in use, it stands in the position shown in full lines in Figure 2, where it 75 is out of the way of the user's nose and chin and does not obstruct the view of the user's lips in a mirror. To apply the cover, the lipstick is first drawn into the container and then the cover is pushed up to the position shown in dot-dash 80 lines in Figure 2, the slide 18 moving upwardly. The cover is then swung in an arc into position over the mouth of the container, and telescopically applied to the container, bringing it to the position shown in Figures 1 and 3. 85

The carrier 6 is reciprocated in the tubular guide 1 (and the lipstick projected from or retracted into the container) by simply effecting relative rotary movement between the exterior casing 12 and the operating head 2. In such 90 relative movement the operating sleeve 9 moves with the exterior casing 12, being held thereto by springiness and friction after the manner in which a piece of paper is held in a mailing tube. Considering the operating head 2 as being held stationary, the slot 4 in the guide tube 1 permits vertical movement of the pin 8 and carrier 6, the edges of the slot 4 forming spaced vertical shoulders which guide the pin 8. The helical slot 10 in the sleeve 9 is angularly inclined with respect to the slot 4 and also the edges of slot 10 form inclined shoulders which engage the pin 8. Thus when the sleeve 9 is rotated by rotating the exterior casing 12, the shoulders constituting the edges of slot 10 cam the pin 8 either 105 up or down in vertical slot 4 (depending upon the direction of rotation). The lipstick is thereby projected from or retracted into the container.

Lipsticks, etc., are of various consistencies, and, 110

cup 6 is adapted to receive various sticks. A stick of firm consistency need be inserted only to inwardly pressed bead 6^a which acts as a convenient stopping point. A soft stick may be inserted to shoulder 6^b, the pin 8 cutting a notch in the bottom of the stick. A hole 6^c allows the air to pass out of the cup as the stick is inserted.

It will be seen that the present invention provides various features giving practical advantages in manufacture of parts, assembly, and use. Various modifications of the construction may, of course, be made, so the particular disclosure is not to be considered as limiting the scope of the claims. For example the tubular construction disclosed is of circular cross section, but certain features of the invention are applicable to tubular constructions of rectangular or other non-circular cross section.

I claim:

1. A container for housing material and holding it for use comprising: a slotted cylindrical guide having an operating head and an exterior annular groove adjacent said head; a slotted sleeve rotatably embracing the cylindrical guide, the sleeve having means which interlocks with said groove to prevent longitudinal movement of the sleeve with respect to the cylindrical guide; a casing embracing the sleeve and manipulatable to rotate the sleeve on the cylindrical guide; a carrier for material slidable in the cylindrical guide, a stud on the carrier engaging the slots of the cylindrical guide and the sleeve, said slots being relatively inclined whereby rotation of the sleeve on the cylindrical guide moves the carrier lengthwise, the sleeve having a longitudinally extending portion cut away to form a guideway; a slide reciprocatable in said guideway; and a cover for the container pivoted to said slide.

2. A container for housing material and holding it for use comprising: a slotted cylindrical guide having an operating head; a carrier for material slidable in the cylindrical guide, the carrier having a stud projecting through the slot of the guide; a sleeve embracing the cylindrical guide, the sleeve having a shoulder engaging said stud and positioned at an angle to the slot in the guide whereby rotation of the sleeve with respect to the guide moves the carrier longitudinally; means to limit longitudinal movement of the sleeve with respect to the tubular guide; a slide reciprocatable in a guideway adjacent the

sleeve; and a cover for the container pivoted to said slide.

3. A container for housing material and holding it for use comprising: an exterior casing having an open end for the projection of material and having a longitudinal slot adjacent said end; means to support material in the casing and project it therefrom for use; a telescopic cover for said casing; cover retaining means slidable longitudinally within the casing independently of the operation of said material supporting and projecting means; and a pivotal connection between said retaining means and the cover, said connection extending through said slot.

4. A container comprising: a slotted tubular casing; a sleeve within the casing, the sleeve having a longitudinally extending portion cut away to form a guideway enclosed within the tubular casing; a slide reciprocatable in said guideway; and a cover attached to said slide, the connection between the slide and cover extending through a slot in the exterior casing.

5. A container for housing material and holding it for use comprising: an exterior casing having an open end for the projection of material and having a longitudinal slot adjacent said end; means to support material in the casing and project it therefrom for use; a telescopic cover for said casing which when applied covers the slot in said casing; cover retaining means slidably longitudinally within the casing independently of the operation of said material supporting and projecting means; and a pivotal connection between said retaining means and the cover, said connection extending through said slot.

6. A container for housing material and holding it for use comprising: an exterior casing having an open end for the projection of material, the casing also having an outwardly projecting bead extending around it below said open end and having a vertical slot extending upwardly from adjacent the bead; means to support material in the casing and project it therefrom for use; a telescopic cover for said casing; cover retaining means slidable longitudinally within the casing independently of the operation of said material supporting and projecting means; and a connection between said retaining means and said cover, said connection extending through said slot.
